EASEL AND NOTEBOOK CONSTRUCTION

Frank Stanley Schade, Holyoke, Mass., assignor
to National Blank Book Company, Holyoke,
Mass., a corporation of Massachusetts

Application July 24, 1939, Serial No. 286,120

14 Claims. (Cl. 281—33)

This invention relates to improvements in notebook holders and has particular reference to that type of holder which is employed with, for instance, a stenographer's notebook to allow the user to set the book up like an easel and read the contents while transcribing dictation on a typewriter.

Patents on devices of this general sort have been issued from time to time but due to the relatively expensive construction, lack of maneuverability, and other disadvantageous features of the disclosed structures, no device of this sort, so far as I know, has come into general and accepted use. My structure not only obviates the difficulties of these constructions as described in earlier patents but in addition has such a simplicity of construction and advantage in arrangement that not only is its field of applicability greatly increased, but its use is rendered practical both from the manufacturer's and consumer's standpoint.

As will appear, my improved structure when added to existing forms of notebooks not only gives the user the inherent advantages of this type of notebook holder, but it also does not hinder or make less available the normal use of the notebook with which it is associated as did the earlier described structures.

The foregoing and other advantages will appear from a reading of the specification taken in conjunction with the accompanying drawings in which:

Fig. 1 is a top plan view of a notebook provided with my novel structure, the notebook being closed;

Fig. 2 is a side view of Fig. 1;

Fig. 3 is a view similar to Fig. 2, but with the notebook set up for use in transcription;

Figs. 4 and 5 are enlarged detail sectional views taken on lines 4—4 and 5—5 of Figs. 1 and 3 respectively;

Fig. 6 is a fragmentary side view showing the book opened for writing on the sheets;

Fig. 7 is a view like Fig. 1 but of a modified form of structure and looking at the back cover;

Fig. 8 is a side view of the structure in Fig. 7 with the notebook set up for use in transcription;

Fig. 9 is a detail sectional view taken on the line 9—9 of Fig. 7; and

Fig. 10 is a fragmentary top plan view showing a modification of the structure of Fig. 7.

Referring to Figs. 1 to 3, I have shown my invention associated with one well-known form of notebook but its equal applicability to other forms will, as the description proceeds, be read-

ily apparent to those skilled in the art. Thus, the notebook consists of a pack of notebook sheets 3 having front and back covers 5 and 6 with a helically wound binding means 7 threaded through holes 8 formed both in the covers and in 5 the sheets adjacent one edge thereof.

Attached to the front cover 5 as, for instance, by adhesive, is an anchor tab 10. It is preferably made of cardboard. A similar anchor tab 11 and a saddle or guide 12 are likewise secured to the 10 back cover 6. As is apparent in Figs. 1, 4 and 5, each anchor tab 10 and 11 as well as the saddle 12, has its upper portion unsecured to its respective cover to allow a limited hinging action. The anchor tabs 10 and 11 have eyes 14 and 15 and the saddle 12 a hole 15 formed in their respective loose upper portions.

A longitudinally yielding flexible bow-string or connector 16 of any suitable composition such as plain rubber, an elastic cord or its equivalent, 20 such as a fine spring with very small coils, is attached by anchor members 17 to each of the anchor tabs 10 and 11 and threads the hole 15 in saddle 12, see Figs. 2 and 5. As is plain in Fig. 4, each anchor member is in the form of a sleeve 25 which is crimped about the extremity of the connector 16 and has a hook-shaped end 18 which is hooked into the eye 14 of each anchor tab. In assembly, the anchor tabs 10 and 11 and saddle 12 are secured to the covers as illustrated. 30 Then the bow-string 16 with the anchor members attached is secured to one anchor tab, the connector 16 threaded through the hole 15 in the saddle and the second anchor member 17 hooked into the eye 14 of the other anchor tab. 35

The distance around the outside of the covers between the anchor tabs 10 and 11 is always about as shown and the bow-string 16 is cut so that for the length between tabs it is under only a moderate tension which is sufficient to keep it 40 snugly against the covers when the book is in the flat position of Fig. 6. On the other hand, the tab 10 and saddle 12 are located about opposite each other as indicated, and preferably at a distance from the hinge about a quarter to a 45 third of the distance from the binding edge, to properly guide the bow-string as the covers are placed in various positions. Also the saddle serves to hold the bow-string taut in the position of Fig. 3 so that the covers will not "spread eagle" 50 as they would if the bow-string of the length shown and under a moderate tension in the closed position of Figs. 1 and 2 spanned directly from anchor tab 10 to tab 11. This arrangement is very effective in prolonging the useful life 55

of the bow-string for by keeping merely a slight tension on the bow-string there is less chafing of the bow-string 16 by the edges of the covers and saddle when the book is being opened and closed from the positions of Figs. 2 and 6. The exact locations of anchor tabs 10 and 11 and saddle 12 are not, however, critical and can be varied to suit the particular notebook on which the holder is being installed. Therefore, by the use of the two anchor tabs in combination with the saddle the notebook holder can be attached in the best position for obtaining the most satisfactory operation under all circumstances.

When it is desired to copy from the notebook the cover 5 is swung about the binding means 7 from the position of Fig. 2 to that of Fig. 3 where it forms the back support for the cover 6 and the pack of sheets 3. In this position the connector 16 acts as a tie rod to keep the notebook in the position indicated, the saddle 12 forming a support for the bow-string. The exact angle between the covers 5 and 6 in the position of Fig. 3 is determined by the relative weight of the various notebook parts in relation to the tension of the bow-string or connector 16. The position shown is approximately the normal one. It is obvious, however, that the angle between covers 5 and 6 can be varied somewhat by simply pressing down on the binding means, for the bow-string 16 can slacken off or assume a slight tension. The covers will ordinarily retain this new angle if the change is not too great, due to the weight of the book or friction between the lower edges of the covers and the surface on which the notebook is resting.

As is clear from the drawings, as the sheets are read they may be turned around the binding means 7 so that they lie on the cover 5. The drawing in Fig. 3 shows part of the sheets in that position now, but with the main portion on cover 6. Of course, either side of the sheets may be read depending on which cover is facing the reader. Also, referring to Fig. 6, the notebook can easily be laid down flat on the table and be written on as with the usual notebook having no holding device.

As is apparent from the drawings, all of these operations can be carried on at will by the user and his only problem is the simple one of placing the notebook in the desired position. The notebook holder adapts itself to the various positions of the notebook automatically. This is particularly evident from an examination of Figs. 3 and 6, where it can be seen that the notebook holder not only performs its function of holding the notebook in position in the former figure when the notes are being referred to, but also lies flat against the covers and interferes in no way when the book is being written in.

Another feature of the structure of Figs. 1 to 6 is the fact that all of the parts that go to make up the notebook holder lie on the outside of the covers and are attached thereto. This arrangement has a two-fold advantage. In the first place, there are no humps on the inside of the covers, underlying the notebook sheets and therefore the notebook can be written on in its flat position of Fig. 6 down to the last sheet, and the user insofar as his writing is concerned, is completely oblivious of the fact that the notebook holder is in the book. This is so, no matter on which cover the particular sheet being written on is lying.

In the second place, the notebook holder can be attached to any notebook without any cutting

or special fitting operation because it is attached wholly to the outside of the covers and this includes those notebooks having sewed bindings as well as the one shown. Furthermore, the retail dealer and the user can themselves attach the easel accessory to the customary notebooks.

Referring now to Figs. 7 to 9, the structure can be somewhat modified as indicated to eliminate the anchor tabs 10 and 11 and saddle 12 where a bow-string is used in which the ends are joined to form a continuous loop. In the following description I will disclose my arrangement where a rubber band serves as a bow-string but its equal applicability to other forms of bow-strings will be readily apparent to those skilled in the art. Cover 6, see Fig. 7, has cut in it a series of triangular slits 20 terminating in holes 21. Directly above these slits 20 are a pair of holes 22. The slits 20 with the holes 21 receive and hold one looped end of a rubber band 24 which serves as a bow-string as shown. The band 24 is then passed through the holes 22, over the edge of cover 6 and is secured to the other cover 5 by means of a similar arrangement or simply by another triangular slit 20' located in the second cover.

When the book is opened to the position of Fig. 8, the rubber band holds the covers as shown. In this case, the holes 22 in cover 6 serve the function of saddle 12 in the earlier described arrangement.

By providing several slits 20 as shown, the tension of the band 24 can be varied according to the length of the band so that it is not under undue tension when the book is closed as in Fig. 7. Also, the holes 22 are made so that the band 24 passes through them easily, and this allows the band to assume the position of Fig. 8 without binding so that the portion of band at 25 is not under a high tension with the portion at 26 relaxed. By this arrangement it is possible to insure maximum life to the band and not cause the user the trouble of replacing it before the book is filled during normal use.

With this arrangement, as appears in Fig. 9, the looped end 27 of the band lies between the outer of the sheets 3 and the cover 6, and might cause a hump on these sheets which would interfere with writing thereon. However, this difficulty may be solved by making the two outer sheets 28 of thicker material to present a smooth backing for writing on the remaining sheets.

Referring to Fig. 10, the slits 20 and 20' and holes 22 can be replaced as indicated by the two tongues 30 and 31, respectively, formed by cutting substantially semi-cylindrical portions out of the material of the covers and providing the tongues with holes 32 and 33. The rubber band 24 is then attached as indicated.

The arrangements shown by Figs. 7 to 10 have the disadvantage that some cutting is necessary to provide for the attachment of the band 24, but they do provide an exceedingly neat and inexpensive structure in which the bow-string can easily be replaced by the user in case of failure. From the standpoint of the manufacturer these forms are particularly convenient as the necessary operations to prepare the book for the attachment of the bow-string are easily and inexpensively made and do not affect the functioning of the notebook even though the bow-string is not included.

As indicated above, the covers 5 and 6 may be formed differently, as shown, or they may both be made like the cover 6. The second method has

the advantage of imposing less strain upon the band 24 since it has greater length on each side of the hinge binding, and also permits the covers to be made with a single cutting die and without the necessity of handling the covers throughout their manufacture in two distinct groups. The first method leaves one cover more nearly free of the band, which is advantageous in case it is to bear printing.

10 Finally, the notebook holder because of its arrangement, even though it is a fixture added to a notebook, adapts itself so easily and unobtrusively to the various positions of the notebook that its advantages of operation are not, as with devices described in early patents, overridden by the difficulties of using the holder to perform its function or of disposing of the holder when it is not being used in its function.

As is apparent from the above, my conception 20 of a new means to accomplish the desired function not only obviates the difficulties of the structures described in earlier patents but also has such a simplicity of construction and advantageous arrangement that not only is its field of applicability increased but it also contributes substantially to the art in providing a structure which is practical, useful and desirable, from the manufacturer's, the retailer's, and the consumer's standpoint.

30 What I claim is:

1. In a notebook holder of the type described, a yielding bow-string, a pair of anchor tabs, and means to attach the ends of said bow-string to said anchor tabs, said tabs and bow-string being arranged to be attached wholly to the outside covers of a notebook with one tab attached to each cover and the bow-string passing over the binding edge of the notebook for the purpose described.

40 2. In a notebook holder of the type described, a yielding bow-string, a pair of anchor tabs, means to attach the ends of said bow-string to said anchor tabs and a third tab having guiding means thereon to support said bow-string, said tabs and bow-string being arranged to be attached wholly to outside covers of a notebook with one anchor tab and the third tab on one cover and the second anchor tab on the other cover with the bow-string passing over the binding edge of the notebook for the purpose described.

50 3. In combination with a notebook having a pack of sheets bound together along one edge and outer covers between which said pack of sheets is contained, a notebook holder consisting of a pair of anchor tabs, one attached to the outside of each cover, a yielding bow-string stretched between said tabs on the outside of said covers and passing over the binding for said pack, and means to attach said bow-string to said anchor tabs.

60 4. In combination with a notebook having a pack of sheets bound together along one edge and outer covers between which said pack of sheets is contained, a notebook holder consisting of a pair of anchor tabs, one attached to the outside of each cover, a yielding bow-string stretched between said tabs on the outside of said covers and passing over the binding for said pack, means to attach said bow-string to said anchor tabs and a third tab attached to one of said covers intermediate one of said anchor tabs and the bound edge of said pack, said third tab having 70 means to guide and tension said bow-string as

the notebook is placed in various positions for the purpose described.

5. The structure of claim 4 with said third tab being located substantially opposite the anchor tab on the other cover.

6. The combination of a notebook and an easel construction, the latter consisting of an elastic cord having one end anchored on the outside of one book cover close to the bottom cover edge, said cord extending up and over the bound edge 10 of the book and anchored on the outside of the other cover a substantial distance below the bound edge, said elastic cord being under sufficient tension when the book is closed to keep the cord snugly against the book and when open to 15 act with the covers as an easel for the book.

7. The combination as pointed out in claim 6, having tabs stuck to the covers to anchor the elastic cord at the ends.

8. In a stenographer's notebook or the like having a pair of stiff covers, a filler, and a spiral wire binding passing through the covers and fillers, an elastic member secured at its ends to the covers and passing between the wires of the spiral binding and supporting means intermediate the ends 20 of said elastic member and carried by one cover to slidably support said elastic member for the purpose described.

9. In a stenographer's notebook or the like having a pair of stiff covers and a hinge-like binding, an elastic member passing across the binding margin and connected with the covers at a distance from the binding margin on the order of a quarter to a third of the length of the cover, at least one of the covers having said connection 30 slidably and having an anchorage for the end of the elastic member remote from the binding margin.

10. A stenographer's note book or the like having a pair of stiff covers and a hinge-like binding, 40 at least one of said covers having a pair of spaced apertures positioned at a distance from the binding margin on the order of a quarter to a third of the length of the cover and a cut-out tab at a greater distance from the binding margin, an 45 elastic band looped about said tab and extending successively through the holes and over the binding, and a device on the second cover about opposite said holes for engaging the second end of the band.

11. A stenographer's notebook or the like having a pair of stiff covers and a hinge-like binding, both of said covers having a pair of spaced apertures positioned at a distance from the binding margin on the order of a quarter to a third of 55 the length of the cover and a cut-out tab at a greater distance from the binding margin, and an elastic band looped about each of said tabs and extending successively through the holes and over the binding.

12. A stenographer's notebook or the like having a pair of stiff covers and a hinge-like binding, one of the covers having a pair of spaced apertures positioned at a distance from the binding margin on the order of a quarter to a third of the length of the cover and a cut-out tab at a greater distance from the binding margin, a cut-out tab in the second cover about opposite said holes, and an elastic band looped about said tabs, extending over the binding and successively 60 through the holes.

13. A stenographer's notebook or the like having a hinge portion, an elastic member extending around the hinge portion, means to anchor the extremities of the member to the covers, and sup- 75

porting means intermediate the anchor means and carried by one cover, to slidably support the elastic member in an angular path between said anchored extremities when the notebook is open and in easel position as described.

14. In a stenographer's notebook or the like having a pair of stiff covers and a hinge-like binding, an elastic member passing across the binding margin, means to connect the elastic

member with the covers at a distance from the binding margin on the order of a quarter to a third of the length of the cover, and supporting means intermediate said connecting means and carried by one cover and in sliding engagement with said member to support said member in an angular path between said covers when the notebook is open and in easel position as described.

FRANK STANLEY SCHADE.
